AUTOMOBILE RADIO RECEIVER

Donald H. Mitchell, Chicago, Ill., assignor to
Galvin Manufacturing Corporation, Chicago,
Ill., a corporation of Illinois

Application March 22, 1933, Serial No. 662,032

5 Claims. (Cl. 250—20)

My invention relates to radio receivers. It relates more in particular to the elimination of ignition interference in a radio receiver installed in an automobile or similar motor driven vehicle.

5 In the installation of radio receivers in automobiles, it is customary to mount the chassis at a convenient location on the bulk head; the speaker at a convenient location within the passenger compartment of the car, sometimes at another 10 portion of the bulk head, and the control means for the receiver at some distance from the chassis, usually on the automobile steering post. The position is not always exactly as indicated, but in substantially all cases the chassis, speaker 15 and power supply are separately mounted and are interconnected by cables. These cables are a source of interference pick-up and it is customary to shield them heavily by means of continuous braided shielding material in an attempt 20 to avoid the interference resulting from the close proximity to the motor ignition system. I have found that the types of cables heretofore required are expensive to manufacture and maintain, and further are not completely satisfactory 25 from the noise elimination standpoint. It appears that if there is any possibility whatsoever of stray high frequency currents entering any portion of the receiver in an ordinary automobile installation, such stray current will manifest 30 itself in the form of noise.

The principal object of my present invention is the provision of improved means for eliminating noise in a radio receiver of the character described.

35 Another object is to avoid objectionable stray current pick-up in the cables connecting one portion of the installation to another.

Another object is to avoid the use of shielding in connecting cables.

40 Other objects and features of the invention will be apparent from a consideration of the following detailed description taken with the accompanying drawing, in which

The single figure is a circuit diagram showing 45 the application of my invention to a radio receiver but indicating schematically certain features thereof.

In the embodiment shown, I have applied my 50 invention to a radio installation which employs in the receiver portion a superheterodyne type of circuit and a dynamic type of loud speaker. Power is supplied to the set from the ordinary car battery, usually six volts, by power supply device including an interrupter, transformer and 55 rectifying device. The present invention con-

cerns itself principally with the battery cable which supplies all of the power to every portion of the receiver; and the speaker cable which includes the conductor running to the voice coil and the conductor running to the dynamic speaker field coil. Each of these cables employs only a single conductor for each circuit, one side of each circuit being grounded. The chassis itself is mounted in a metal container. Within the chassis container and shielded from each other I provide a plurality of relatively very low resistance air core choke coils through which the current passes, the coil in each instance being part of the circuit. At one side of the coil I ground the conductor through a suitably designed condenser whereby to by-pass the high frequencies to ground.

Consider first the battery cable and the utilization of the present invention in connection therewith. The usual car battery 10 has one 20 terminal grounded at 11 and to the other terminal a conductor 12 is connected running to a main switch 13 forming a part of the receiver. The receiver itself is placed within a shielded container 14 which is grounded at 16 to the automobile car frame. Between the main switch 13 in the end of conductor 12, I connect a choke coil 17 designed to pass the battery voltage without appreciable resistance but being inductively wound to offer a resistance to high frequency 30 currents which may be picked up on the battery cable conductor 12. On the input side of the choke coil 17 I connect the conductor 12 to ground through a condenser 18. With the type of circuit shown and which will be referred to 35 somewhat hereinafter, I have obtained good results when the coil 17 comprised twenty turns of No. 14 copper wire wound on a one-half inch dowel and in which the condenser 18 had a capacity of 0.25 microfarad. Preferably a shield 40 19 is placed around the choke coil 17. In connecting one side of the condenser 18 to ground I find that good results are obtained by connecting directly to the metal container 14. In the preferred form, both the condenser 18 and the 45 ground connection are arranged outside of the container 14.

It will be understood that current in the conductor 12 is normally flowing from the battery to the power supply device. Since the power supply device includes a filter circuit, there is slight possibility of stray pick up on the conductor 12 entering the receiver through the power supply device. In customary practice in automobile radio installations, however, the six volt direct cur- 55

rent from the battery is delivered directly to the heater elements of the tubes and to the field coil of the speaker. Through either connection, particularly those to the heater elements of the tubes, interference may be introduced into the receiver unless means is employed to prevent it. Since all of the power delivered to the receiver is from the conductor 12, my method of preventing stray high frequency currents from filtering back into the receiver avoids any possibility of interference from this source. As a consequence, in my installation ordinary suitably insulated wire can be used in place of the usual shielded cable.

The complete description of the circuit employed in the receiver is not essential to an understanding of the present invention. A brief reference to portions thereof will be made, however, to facilitate an understanding of further use of the principles of the present invention.

When the switch 13 is closed, battery voltage is delivered to a conductor 21 connected to one side of the switch and from the conductor 21 through suitable connections including jacks 22 (my copending application, Serial No. 639,081, filed October 22, 1932, describes the use of these jacks) to an interrupter and converter 23. The plate voltage is supplied to the receiver through the device 23, a portion thereof flowing through a filter circuit as shown and a portion being unfiltered, it being understood that in the final stages the higher frequencies will not affect the voice frequencies sufficiently to be objectionable.

The circuit employed is the superheterodyne type and includes automatic volume control and other features now in common demand. The final stage is a push-pull stage including tubes 24 and 26, the output of which is delivered through suitable connections shown to an output transformer 27. The secondary of the output transformer has one terminal grounded and the other terminal connected to a conductor 28 running to a voice coil 29 of the speaker. The speaker is indicated schematically and includes a cone 30, to which in customary practice the voice coil 29 is secured. A field coil 31 is employed with the dynamic type of speaker and has one end grounded and the other end connected to a conductor 32 which through suitable connections supplies six volt current to the field coil.

In the customary arrangement, the conductors 28 and 32 will together constitute a single cable, usually termed the "speaker" cable; or they may be separate cables depending upon the particular design of the set. It is customary practice to shield this type of cable thoroughly. It is understood, however, that higher frequencies picked up on the cables 28 and 32 will not have any direct effect upon the operation of the speaker. Through such cables or conductors, however, stray high frequency currents can be fed back into the receiver and either through inductive connections or direct conductive connections will so affect the receiver itself as to manifest themselves in the form of noise. I am able to employ substantially the same arrangement on this type of conductor as described herein above in connection with the battery cable to prevent interference from this source.

First considering the conductor 32 connected to the field coil, I employ an inductively wound coil 33 connected directly into the conductor and shielded by a shield 34. One end of this coil is grounded through a condenser 36 to provide a high impedance path to ground through which

the high frequency current will be filtered but which will not affect lower frequency current.

The feeding back of high frequency currents through the voice coil conductor 28 is prevented in the same way. A coil 37 is connected into the conductor on the inside of the chassis between the terminal of the conductor 28 and the secondary of the output transformer 27. This coil is provided with a shield 38 and has one side grounded through a condenser 39. Both the coils 33 and 37 may consist of twenty turns of No. 14 copper wire wound on a one-half inch dowel. The condenser 36 with the design of set which I show preferably has a capacity of about .1 microfarad, while good results are obtained if the condenser 39 has a capacity of .003 microfarad.

Since the source of power for an automobile receiver of the present design is a standard type of six-bolt battery, I prefer to feed the battery current directly to the heater elements of the tubes. To this end, a conductor 41 having a suitable connection to battery through the conductor 21 is employed to feed the current to the heater elements of the tubes, as shown. I have found that a quieting effect is obtained if an inductively wound coil 42 is connected into the conductor 41 and provided with a shield 43. One side of this coil may be grounded through a condenser 45, if desired, but I have found in some instances that the distributed capacity of the wires leading to the receiver is sufficient to balance the inductance of the coil 42 and no separate condenser is required. The coil 42 also may consist of twenty turns of No. 14 copper wire wound on a one-half inch dowel. It should be remembered that as far as each of the coils 17, 33, 37 and 42 are concerned, they should not be such as to increase the resistance to the passage of currents normal to them while having sufficient resistance to act as chokes insofar as stray high frequency currents are concerned.

When employing the present invention, I can also use novel means for attenuating stray antenna pick up. This novel means is described in detail in my copending application, Serial No. 642,162, filed November 11, 1932. In order that the entire means for eliminating noise in a receiver such as shown may be understood, however, I have illustrated one means of eliminating stray antenna pick up employing the principle described in my copending application.

A main antenna 46 of the type usually carried in the roof of a car is employed and connected by a conductor 47 to one end of the coil 48, the opposite end of which coil is grounded at 49. An auxiliary antenna 51 of smaller size is provided and is located so as to pick up the stray frequencies which will be picked up by the antenna 46. If the antenna 46 is located in an automobile, for example, it will pick up some of the ignition frequencies. The antenna 51 will then be located in a heavy ignition field, as, for example, under the engine hood. The antenna 51 has a lead-in conductor 52 connected to one end of the coil 53, the opposite end of the coil being grounded. The coils 49 and 53 are variably coupled so that they can be tuned in such a way as to cause the coil 53 to buck out or attenuate all of the undesirable frequencies impressed upon the coil 48 by the antenna 46. The coils 48 and 53 together are supported in a shielded container 54. The coil 48 is suitably connected to the primary of a radio frequency transformer which forms a part of the first stage of the receiver.

I have shown the various coils employed in accordance with my present invention for suppressing interference as being separately shielded. It will be understood, however, that many different ways of shielding these coils may be employed. In the preferred construction, I employ a metal cabinet as shown in my co-pending application, Serial No. 639,081, filed October 22, 1932, and merely provide separate compartments for each one of the coils 17, 33, 37 and 42. These are structural features, however, and it is well understood that various structural expedients can be employed for utilizing the principles I have established.

15 As far as each of the by-pass condensers 18, 36, 39 and 45 are concerned, it will be well understood by those skilled in the art that I may employ any suitable means for securing the same result, namely, a high capacity impedance path to ground, so related to the choke coils as to cooperate with them. Portions of the wiring in certain cases, for example, may have sufficient capacity effect to make the use of a separate condenser unnecessary. In other words, any electrical arrangement including an inductance and capacity can be used which together function to pass the lower frequencies but filter out or bypass the higher undesirable frequencies.

30 I have described my invention in detail giving actual illustrative electrical values for various portions of the apparatus, but it is obvious that I am not restricted to the specific details shown and described, and the invention is limited only by the appended claims.

35 What I claim as new and desire to protect by Letters Patent of the United States is:

1. In an automobile radio installation, means for suppressing the effect of undesirable outside current frequencies, a radio receiver having a grounded metal shielding cabinet, an interrupter converter power supply means within the cabinet for converting direct battery current to alternating current for plate supply, a conductor connecting a terminal of the usual automobile storage battery to said power supply means, a low resistance coil and shunt condenser connected to said battery conductor between the battery and the power supply, a dynamic speaker having a voice coil and field coil positioned outside the receiver cabinet, a connection from the speaker field coil through a radio frequency choke with a by-pass condenser to a connection from the battery but at a point beyond the first said low resistance coil and condenser whereby current is fed from the battery to the field coil through the low resistance coil and the radio frequency choke, and a radio frequency choke and by-pass condenser connected between the voice coil and the receiver.

2. In an automobile radio receiver, means for suppressing the effect of undesirable outside current frequencies including a grounded metal shielding cabinet, an interrupter convertor power supply within the cabinet for converting direct battery current to provide a plate supply for the receiver, an automobile storage battery, a dynamic speaker positioned outside and independent of the shielding cabinet and having a voice coil and field coil, a single conductor from the ungrounded ter-

5 minal of the storage battery extending into the receiver cabinet and connected to the interrupter convertor power supply, said battery conductor supplying all of the power to the receiver and dynamic speaker, a low resistance coil in series with said battery conductor and a shunt condenser connected to the battery conductor between the battery and said convertor power supply means, a connection from the speaker field coil to the battery supply at a point between the low 10 resistance coil and convertor power supply means, a low resistance choke coil in series with the conductor extending to the field coil with a by-pass condenser having one terminal connected to said conductor between the field coil and low resist- 15 ance choke coil, and a third conductor from the voice coil of the speaker extending inside the shielding cabinet.

3. In a radio receiver system for vehicles having an ignition system, a storage battery for direct current supply to said receiver system and said ignition system, a radio receiver in said receiver system, and an externally mounted loud speaker, external current supply lines to said radio receiver and to said loud speaker, and means in 25 said lines for eliminating ignition interference picked up by said lines to prevent said interference from entering said radio receiver, said means comprising a radio frequency filter in each of said lines including an inductance and a capacitance. 30

4. In a radio receiver system for vehicles having an ignition system, a storage battery for direct current supply to said receiver system and said ignition system, a radio receiver in said receiver system, and an externally mounted loud speaker 35 having a voice coil and a field coil, external current supply lines to said radio receiver, said voice coil and said field coil and means in each of said lines for eliminating interference picked up by said lines to prevent said interference from entering said radio receiver, said means comprising a filter in each of said lines including an inductance and a capacitance. 40

5. In a radio receiver system for vehicles having an ignition system, a storage battery common to 45 said receiver system and ignition system, a radio receiver chassis having a receiver circuit thereon, a loud speaker employing a field coil and voice coil mounted on said vehicle away from said radio receiver, and an antenna for said receiver system 50 external of said radio receiver chassis, external supply lines from said antenna to said receiver circuit, from said battery to said receiver circuit, and to said speaker voice coil and to said speaker field coil, means for eliminating ignition interference 55 picked up on said external circuits and preventing the same from entering the receiver circuit, said means including a balancing unit comprising a pair of variably coupled inductance coils in electrical connection in the line from the antenna to said receiver, and a radio frequency filter in electrical connection in each, the supply line between the battery and the radio receiver circuit, the supply line between the speaker field coil and receiver circuit, the supply line between 60 the speaker voice coil and receiver circuit. 65

DONALD H. MITCHELL.
